UNITED STATES PATENT OFFICE.

AXEL LEONARD ZETTERMAN, OF NEW BRITAIN, CONNECTICUT, ASSIGNOR OF ONE-HALF TO EDWARD NELSON, OF NEW BRITAIN, CONNECTICUT.

CHISEL HANDLE.

1,409,638.

Specification of Letters Patent. Patented Mar. 14, 1922.

Application filed April 20, 1921. Serial No. 462,798.

To all whom it may concern:

Be it known that I, AXEL LEONARD ZETTERMAN, a citizen of Sweden, residing at New Britain, in the county of Hartford and State 5 of Connecticut, have invented certain new and useful Improvements in Chisel Handles, of which the following is a specification.

My invention relates to improvements in chisel handles, having reference to the handles of wood that are applied to carpenters' chisels, and the object of my improvement is to improve the butt end that receives the blows of the hammer or mallet by means of the application to the said butt end or 15 butt of a cap of special form to the end of the handle body, and involving a special shaping of the said end for cooperating therewith, whereby there will be provided a special cushioning device having special advantages in use and also providing a protection for the said end of the handle body.

In the accompanying drawing:—

Figure 1 is a side elevation of a carpenter's chisel that is provided with a handle 25 that embodies my improved cap at the butt end.

Figure 2 is a side elevation on an enlarged scale of the butt end portion of the structure that is shown in Fig. 1.

Figure 3 is a plan view of the same, being in part broken away.

Figure 4 is a sectional view on the line 4—4 of Fig. 3.

Figure 5 is a side elevation of the butt 30 end of the handle body with the cap removed.

Figure 6 is a bottom view of the cap.

My improved chisel handle comprises a handle body 10 of wood that is applied to 40 the blade structure 11 of a carpenter's chisel in the usual manner and that has applied to the butt end portion 12 a cap structure 13 of special form and material constructed and arranged to receive the blows from the hammer or mallet in use and to serve to cushion the effect of the said blows and also serve as a protection for the said end portion 12 so as to enhance the life thereof.

To this end the cooperating parts of the 50 said handle end portion 12 and cap structure 13 are of special character, as will be described.

Considering the feature of the end portion 12 of the handle body 10, the upper end face

thereof has the outer and major portion 55 faced off flat and radial so as to provide an annular platform 14 and extending upwardly from the said platform 14 and along the axis is an integral tenon 15 of appreciable length.

In use it is the said platform 14, of annular form as mentioned and exterior to the tenon 15, that receives the effect of the blows through the medium of the cap structure 13 that is seated thereon.

The said cap structure 13 has for the exterior a cylindrical side wall 16 and the top end face 17 may be flat as shown or more or less rounded, any desired shape being provided for the exterior form or contour.

The bottom face 18 is in the form of an annular seat or base that is a fit for and adapted to cooperate with the opposed platform 14 on the handle end portion 12.

Extending upwardly from the base 18 is a 75 recess or socket 19 having a cylindrical form that is a fit for the tenon 15 along the peripheral portion of the said tenon 15.

As to the length or depth of the socket 19 relatively to the length of the tenon 15 it 80 will be noted that with the base 18 seated on the platform 14 there is provided a positively open space 20 between the tip end face 21 of the tenon 15 and the opposed end wall 22 of the socket 19.

Thus the open space 20 serves to provide clearance between the top end wall portion 23 of the cap 13 and the opposed end face of the tenon 15.

The effect of the construction and arrangement described is to protect the tenon from the effect of blows that are directed upon the top end face 17 and to insure that the effect of such blows will be received by and sustained by the platform 14.

Because of the operative conditions described it is desirable to make the platform 14 relatively large and make the cross-section of the tenon 15 small or appreciably reduced. As the tenon serves to hold the cap in place, this should have appreciable length. That is to say, the tenon should be long and slender.

In order to provide for such a construction of the tenon 15 and at the same time insure 105 strength and serviceability to the part I may provide some form of reinforcement therefor such as the metal rod 24 shown, which ex-

tends downwardly through the tenon 15 and for an appreciable distance into the handle body 10.

It is important now to note the material of which the cap 13 is made.

While certain materials known as composition or hard rubber may be used, these are not entirely satisfactory.

The one material that I have found to be satisfactory after extensive trials is celluloid, and which is superior to all others.

By providing the clearance space 20 between the end face 21 of the tenon 15 and the opposed end wall 22 of the socket 19 means are provided for permitting the top end wall 23 of the cap 13 to yield under conditions of use, responsive to the effect of blows applied to said top end wall 23. Such yielding is momentary only, the cap being restored after the blows to the original form, due to the resiliency of the material of which it is made, which material, as mentioned, is celluloid.

The cap, made of celluloid as described, will last indefinitely, being practically indestructible under the usual conditions of use. Also, the material mentioned is readily obtainable and is adapted to be fashioned by ordinary methods to the particular form required.

The tenon 15, as mentioned, is integral with the handle body 10, the material for these parts being wood. The provision of the clearance space 20, therefore, permits of leaving the end face 21 of the tenon 15 in relatively rough and unfinished condition and precision as to the length of said tenon 15 is avoided, which is an advantage in the detail of manufacture of the handles.

The tenon 15 being of appreciable length serves to sustain the effect of side blows on the butt of the handle, and, being integral with the body 10, relieves said body of the effect of such side blows.

The clearance space 20 is preferably relatively shallow or thin. This permits of extending the tenon well up into the interior of the cap 13 and extending the length of the opposed and coacting surfaces for the cylindrical wall of the tenon and the border wall of the socket 19, which surfaces serve as the means for retaining the cap in place.

I claim as my invention:

A handle having a celluloid blow receiving cap united therewith by a tenon inclosed socket joint arranged so that the blow may be transmitted to the annular surface surrounding the joint.

AXEL LEONARD ZETTERMAN.
